METHOD OF RETAINING CREASES IN TROUSERS

Louis G. Bowman, St. Louis, Mo., assignor to
 Lewis Invisible Stitch Machine Company, St.
 Louis, Mo., a corporation of Maine

Application October 17, 1936, Serial No. 106,222

4 Claims. (Cl. 2—231)

This invention relates to a new and useful method of retaining creases in garments, such as trousers, coats, or other tubular articles.

Among the several objects of my invention are to provide a method of stitching a tape to a non-creased trousers or body fabric, or to a pre-creased body fabric at points on opposite sides of the line of ridge or crease whereby the crease will be retained and the trousers will be prevented from bagging at the knees; and to provide such a method wherein the tape is applied during a single sewing operation.

With these and other objects in view which will more fully appear, the nature of the invention will be more clearly understood by following the description, the appended claims, and the several views illustrated in the accompanying drawings.

In the drawings:

Figure 1 is a front elevation of a pair of trousers equipped with my invention.

Figure 2 is an enlarged plan looking at the inner face of the body fabric and showing the tape and the single line of blind stitches which connect the tape to the body fabric at points on opposite sides of the line of ridge or crease in the body fabric.

Figure 3 is an enlarged section taken on the line 3—3 of Figure 1 and showing the ridge of tape projecting towards but spaced from the ridge or crease in the trousers.

Figure 4 is a smaller view but showing the ridge of tape in contact with the ridge or crease of the trousers.

Figure 5 is a detail sectional view showing how my method can be carried out by a sewing machine, the view showing the parts in normal positions prior to the formation of stitches, the view also showing the application of the tape to the front section of a trousers leg subsequent to the leg being side seamed, the ridge of tape being spaced from the ridge or crease in the trousers.

Figure 6 is a similar view but showing the needle in position for uniting the tape to the body fabric on opposite sides of the line of ridge or crease in the body fabric.

Figure 7 is a view similar to Fig. 5 but showing the application of the tape to the front section of a trousers leg prior to the side seaming operation.

Figure 8 is a similar view but showing the needle in position for uniting the tape to the body fabric on opposite sides of the line of ridge or crease in the trousers.

Figure 9 is a view similar to Figure 7 but show-

ing the ridge of tape in contact with the ridge or crease in the body fabric.

Figure 10 is a similar view but showing the needle in position for uniting the tape to the body fabric on opposite sides of the line of ridge or crease in the body fabric, and

Figure 11 is a perspective view of the single line of lock stitches.

Like reference numerals designate corresponding parts throughout the several figures of the drawings.

An article constructed in accordance with my method is shown in Figures 1 to 4. This article is shown as comprising a body fabric A, such as a pair of trousers which includes tubular or leg portions 5, 5, each leg including a front section a and a rear section b, the front section being provided with a centrally disposed and outwardly projecting longitudinal ridge or crease 6.

A pre-shrunken non-elastic tape B of woven fabric is secured against the inner face of each leg portion by a single line C of lock stitches of the blind stitch type. This tape extends longitudinally of the leg portion and is centrally disposed with respect to the line of ridge or crease 6, i. e., it extends equally on opposite sides thereof. By employing a tape of non-elastic woven fabric, which has been pre-shrunken, all danger of the tape shrinking and the trousers becoming unshapely when the trousers are subjected to water or to a wet cleaning process is thereby avoided.

A blind stitch sewing machine for carrying out the steps of this method is shown, described and claimed in my co-pending application Serial No. 106,221, filed Oct. 17, 1936, and the finished article is shown, described and claimed in my co-pending application Serial No. 106,223, filed Oct. 17, 1936.

The tape B may be applied to formed and previously creased trousers, by turning each leg inside out and feeding the same through the machine, or the tape may be applied to the front section of a trousers leg prior to the side seaming operation thereof, or the tape may be applied to a trousers leg which has not been creased, either prior to or subsequent to the side seaming operation. If the leg has not been creased, a chalk line is preferably formed on the inner face of the leg as a guide for the operator in directing the leg through the machine.

The single line C of blind stitches includes a needle thread 7 and a bobbin thread 8. The needle thread is formed into a plurality of equally spaced needle thread loops 9 which are con-

55 50 30 25 35 40 45 50 55 60 65 70 75 80 85 90 95

nected by needle thread portions 19, the needle thread loops extending in a plane at right angles to the ridge or crease 6, as shown in Figure 2, and being anchored by the bobbin thread 8.

5 Although my method may be carried out by hand, I preferably employ a blind stitch sewing machine as referred to above. In carrying out this method, I preferably first form the ridge or crease 6 in the front section *a* of each trousers 10 leg or body fabric, and then position the body fabric in a flat plane with the ridge or crease 6 projecting downwardly or outwardly from said plane as shown in Figures 5, 7, and 9. If the trousers have been previously side seamed it is 15 of course necessary to turn the legs inside out, and then feed both superposed sections *a* and *b* through the machine, as shown in Figs. 5 and 6. If the trousers have not been previously side seamed, then the section *a* only is fed 20 through the machine, as shown in Figs. 7, 8, 9, and 10. If the ridge or crease 6 has not been previously formed, a chalk line is made along the inner face of each leg to serve as a guide.

In carrying out the steps in this method, I 25 intermittently feed a superposed tape B and body fabric A through a blind stitch machine which includes a stationary presser foot 11 having an opening 12, a horizontally reciprocatory needle 13 located above the foot and having its path 30 of movement across said opening, a vertically reciprocatory work clamp 14 which cooperates with the underside of the foot to clamp the body fabric and the tape against the foot during the penetrating stroke of the needle, a 35 4-motion feed dog 15 for intermittently feeding the body fabric and the tape past the needle, and upper and lower vertically reciprocatory plungers 16 and 17 respectively which are arranged in alignment and simultaneously move 40 towards each other to clamp the body fabric and the tape therebetween and to retain the crimped fabric and tape while the needle is in the work, and then simultaneously move apart while the needle is out of the work and during 45 the feeding of said work. The upper plunger or crown 16 which is provided with a transverse groove 16a in its under face to receive the needle, is also provided with spaced and downwardly projecting work clamping ribs 18, 19 50 and with a centrally and downwardly projecting ridge forming rib 20, forming resultant grooves 21, 22 therebetween. The lower plunger is provided with spaced and upwardly projecting ridge forming ribs 23, 24 forming a resultant groove 55 25 therebetween which receives the central rib 20 of the upper plunger or crown, the ribs 23, 24 being received in the spaces or grooves 21, 22 of the upper plunger. The lower plunger is provided with horizontal clamping shoulders 26, 27 60 which cooperate with the clamping ribs 18, 19 of the upper plunger to clamp the side edges of the tape and the body fabric therebetween. The bottom of the foot carries a stationary finger 28 which has its rear free end projecting into 65 the opening 12 of the foot.

If the tape B is to be applied to trousers A which have been side seamed and creased, as illustrated in Figs. 5 and 6, the trousers are first turned inside out. One leg of the trousers 70 with the front section *a* above the bottom section *b*, is intermittently fed through the machine together with the superposed tape B which is positioned against the inner top face of the front section *a* and centrally with respect to the downwardly projecting ridge or crease 6 thereof. Each 75

time the feed dog is idle and the needle is out of the work, the upper plunger or crown 16 and the lower plunger 17 move towards each other and clamp the crimped work therebetween. The ridge or crease 6 is positioned under the finger 28 and is held below and in spaced relation to the path of needle travel by said finger, the crease being located in the groove 25 of the lower plunger 17. The center rib 20 of the upper plunger or crown forms a centrally located and downwardly projecting ridge 29 in the tape B which is disposed in the ridge 6 of the body fabric, the apex 30 being located above the finger 28 and consequently in spaced relation to the apex 6a of the ridge or crease 6. The ribs 23, 24 of the lower plunger form upwardly projecting ridges 31, 32 in the body fabric and superposed ridges 33, 34 in the tape, the ridges 31, 33 and the ridges 32, 34 being respectively disposed in the grooves 21, 22 of the upper plunger and in 20 the path of needle travel.

The needle then projects a needle thread loop 9 through the superposed ridges 31, 33 of the body fabric and tape which are on one side of the line of ridge or crease 6, and then through 25 the superposed ridges 32, 34 of the body fabric and tape which are on the other side of said line of ridge or crease 6. The needle thread loop 9 is then anchored by the bobbin thread 8. The needle is then withdrawn from the work, 30 the plungers 16, 17 are separated, the work clamp 14 is lowered, and the feed dog 15 then functions to feed the work a stitch length distance.

It will be observed that each needle thread loop 9 anchors the tape B to the body fabric A on opposite sides of the line of ridge or crease 6, and that said loop passes entirely through the central longitudinal ridge 29 of the tape. The tension of the needle thread loops is such as to maintain the ridge 29 of the tape in its projected relation towards the ridge or crease 6, and consequently the loops constitute braces or ties which function to retain the ridge or crease 6 in shape, while at the same time the non-elastic woven tape, which extends along the leg from a point 40 well below the knee to a point well above the same, functions to retain the trousers leg from bagging at the knee.

It may be desirable to have the ridge 29 of the tape B project fully into the ridge or crease 6 of the body fabric, as shown in Fig. 4, and this is accomplished as shown in Figs. 9 and 10, by reTRACTING the finger 28 to permit the center rib 20 of the upper plunger or crown to form both the downwardly projecting ridges 29 and 6 in the tape 45 and body fabric.

From the foregoing, it will be observed that I first place the tape B on the body fabric A and form the outwardly projecting ridge 6 in the body fabric, and then secure the tape to the body fabric by passing a single line of connected needle thread loops through the tape and body fabric at points on opposite sides of the ridge and in spaced relation to the apex thereof.

It is of course to be understood that the details of structure and arrangement of parts may be variously changed and modified without departing from the spirit and scope of my invention.

I claim:

1. The method of retaining a ridge or crease in 70 a body fabric consisting in first placing a tape on a body fabric and forming an outwardly projecting ridge in the body fabric, and then securing said tape to the body fabric by passing a single line of connected needle thread loops through 75

said tape and body fabric at points on opposite sides of the ridge and in spaced relation to the apex thereof.

2. The method of retaining a ridge or crease in a body fabric consisting in first placing a tape on a body fabric and forming an outwardly projecting ridge in the body fabric, then forming and projecting spaced ridges in the tape and body fabric in the opposite direction to and on opposite sides of the outwardly projecting ridge, and finally securing the tape to the body fabric by passing a single line of connected needle thread loops through the spaced ridges formed in the tape and body fabric.

3. The method of retaining creases in a body fabric consisting in first forming a ridge or crease in the body fabric, then positioning the body fabric in a flat plane with the ridge or crease projecting outwardly, and finally joining a tape to the inner face of the fabric by a single line of

stitches connecting the tape and the fabric on opposite sides of the crease.

4. The method of retaining creases in a body fabric consisting in first forming a ridge or crease in the body fabric, then positioning the body fabric in a flat plane with the ridge or crease projecting outwardly and directing a tape to the inner face of the fabric at the point of the ridge or crease, then projecting ridges of fabric and tape in a direction opposite the ridge or crease of the body fabric and on opposite sides of said ridge or crease and simultaneously forming a ridge in the tape and projecting the same into the ridge or crease of the body fabric, and finally joining the tape to the fabric by a single line of stitches including needle thread loops which pass through the ridges of the fabric and the tape and through the tape ridge in spaced relation to the apex of the ridge or crease in the body fabric.

LOUIS G. BOWMAN. 20
